UNITED STATES PATENT OFFICE.

ADAM HORN, OF BATAVIA, NEW YORK.

BERRY-CARRIER.

SPECIFICATION forming part of Letters Patent No. 593,889, dated November 16, 1897.

Application filed December 28, 1896. Serial No. 617,194. (No model.)

To all whom it may concern:

Be it known that I, ADAM HORN, a citizen of the United States, residing at Batavia, in the county of Genesee and State of New York, 5 have invented certain new and useful Improvements in Berry-Carriers; and I do hereby declare the following to be a full, clear, and exact description of the invention, such as will enable others skilled in the art to which it appertains to make and use the same.

This invention relates to improvements in crates, and has more particular relation to knockdown crates for carrying fruit-boxes.

This invention consists of certain novel constructions, combinations, and arrangements of parts, all of which will be hereinafter more particularly set forth and claimed.

In the accompanying drawings, forming part of this specification, Figure 1 represents 20 a perspective view of the crate embodying my invention extended ready for use, and Fig. 2 represents a side elevation of the same in its closed position.

A in the drawings represents the handle, B 25 the supporting-arms, pendent therefrom, and CC the hinged apertured supports. The said handle A and pendent arms B are formed of a single integral piece of wire bent at its upper end into a loop *a* and having its lower 30 ends bent outward and downward to form said arms B, one of said ends being bent horizontally at its lower end and provided with a hook *b*, adapted to engage and lock into a hook *b'*, formed upon the end of the remaining 35 rod or support. The loop *a* is held firmly in position and braced by a cross-piece *a'*, having a dip or notch *a''* near its middle. Said pendent rods B are connected at intervals by cross-strips *c*, suitably secured thereto. Each 40 of the box-supports C comprises a loop *c'*, having eyes *c''* formed at its opposite ends, said eyes being adapted for the reception of the rods *c*, whereby the box-supports may be turned up or down at will. Each of said 45 supports C is also provided with a cross-bar *c''* and a partition-bar *c'''*, connecting said latter bar and the outer portion of the loop. These two latter bars *c''* and *c'''* divide the support into two apertured supports *c''''* and *c'''''*, respectively, which are adapted to receive and hold the usual berry-boxes. The said supports C are connected at their outer ends by vertical

bars D, formed of two strands of twisted wire, provided at intervals with eyes *d*, adapted to embrace the respective loops of the supports, 55 and thus pivotally connect said supports together. The top supports C are further provided with hooks *d'*, said hooks being adapted to be hooked over the bar *a'* and rest in the notch *a''* for supporting the supports C in horizontal positions.

It will be observed from the foregoing description that when said hooks *d'* are hooked over the bar *a'* upon opposite sides they thus support the top supports, while these supports in turn support the remaining portions C by means of the connecting-rods D. It will also be observed that by unhooking the hooks *d'* the said portions C may be turned either up or down against the rods B, and 70 thus folded into a very compact form, so that the device may be readily carried about from place to place or stowed away in any convenient corner.

My improved crate is very simple and cheap 75 in construction and at the same time is very light, so that it requires very little effort to carry it about with boxes of berries applied therein.

It will further be observed that by the employment of my invention the boxes are prevented from resting upon each other, and the fruit is thus protected and is not liable to become bruised, as is ordinarily the case when the boxes rest directly one upon the other. 85

I preferably provide the handle A with a wooden grip to prevent the same injuring the hand.

Having thus described my invention, what I claim as new, and desire to secure by Letters Patent, is—

1. In a box crate or support, the combination with a suitable handle having pendent supporting-rods, of apertured box-supports hinged on said rods, and hook-bars connected 95 to said supports and adapted to hook over the handle to hold the supports in a horizontal operative position or permit them to descend to close the device, substantially as described.

2. In a box support or crate, the combination with a handle having pendent supporting-rods secured thereto, of a plurality of wire box-supporting frames hinged on said supporting-rods, spaced rods connecting said

frames, and hooks mounted on the top frames and adapted to engage a portion of the handle, whereby said frames are all supported in a horizontal position, but in such manner that 5 they may be doubled either up or down upon the disengagement of the hooks, substantially as described.

3. In a box-support, the combination with a handle having pendent connected arms, of 10 rods connecting said arms at intervals, a plurality of wire box-supports hinged upon said connecting-rods, spaced bars connecting said wire box-supports and hooks mounted on the

top frames and adapted to engage the handle, whereby all of said frames are supported in a horizontal position, but are capable of being doubled up or down against the supporting-arm, substantially as described. 15

In testimony whereof I have signed this specification in the presence of two subscr- 20 ing witnesses.

ADAM HORN.
